UNITED STATES PATENT OFFICE.

LESLIE D. NOBLE, OF DETROIT, MICHIGAN.

FOOT SUPPORT.

Application filed August 24, 1922. Serial No. 583,944.

This invention relates to foot supports particularly for use by people having weak or fallen arches, and the object is to provide a support which may be worn on the foot 5 and insertable therewith in the shoe in correct position to overcome such defects. By the arrangement, as is hereinafter described, the pressure and weight of the body is relieved largely from the arch of the foot 10 so that the same may recover correct position and become strengthened and grow naturally in correct form. Preferably the device is provided with an elastic strap or the like extending in a loop over the support and the 15 foot is slipped through this loop and, by reason of the elastic therein, the support is naturally held in position. It is placed on the foot and tends to retain the position on the foot when in the shoe. The support 20 proper as provided at the forward end is shaped to provide a pad directly beneath the metatarsus bones of the foot to support the same centrally at that point and to secure ease in wearing, the device is formed preferably of sponge rubber or like substance 25 that is yieldable in character to some extent, cork having been used with good results. An additional object of the invention is to provide a foot support of the general character stated, the body of which is formed of a resilient or yieldable material having a 30 pad at the forward end beneath the metatarsal bones and a similar pad directly beneath the arch of the foot on the inner 35 side. These objects and the several novel features of the invention are hereinafter more fully described and claimed, and the preferred form of construction of a foot support embodying my invention is shown 40 in the accompanying drawing in which—

Fig. 1 is a plan view showing the device applied to the foot, the elastic band extending across the foot not being shown.

Fig. 2 is an enlarged plan view showing the upper side of my improved support, the elastic band or webbing being broken away to clearly show the upper surface of the support.

Fig. 3 is a plan view of an alternative 50 form of my improved device.

Fig. 4 is a cross section taken on line 4—4 of Fig. 3.

As will be understood from Fig. 2, the foot support consists of a body of resilient 55 material such as sponge rubber, cork or similar material, the outline in plan being

indicated by the line 1. This is enclosed in a casing formed of cloth or leather parts 2 sewed together at the edges and provided on opposite sides with the side flaps 3 and 4 to which preferably is sewed an elastic webbing 5 which extends across the top of the foot as will be clearly understood from Fig. 4. The elastic 5 is broken away in Fig. 2 exposing to view the shape of the filler member. In Fig. 2 it will be noted by the shade lines that a pad 6 is formed at the forward end thereof and another pad 7 of peculiar form at the rear thereof. The pad 6 is intended to be so positioned on the foot 60 as to come immediately beneath the metatarsus bones while the pad 7 lies immediately beneath the longitudinal arch of the foot. The pad 6 serves to hold the foot from spreading, maintaining the central metatarsus bones somewhat higher than those on each side and together with the pad 7 strengthens and supports the arch of the foot. The insert 1 is shown in section in Fig. 4, and it will also be observed that preferably 65 the insert extends as indicated at 8 in Fig. 2 a slight distance to one side of and into the flap. Both sides, however, may be formed with the extensions 8 if desired. Extensions sometimes may be provided on both sides 70 particularly if the insert is formed as shown in Fig. 3 with a single pad 6^a only for use beneath the metatarsus bones. Oftentimes this is the only correction needed and when such is the case the pad 7 beneath the arch is 75 not required. In this type the extensions 9 and 10 on each side extend into the flaps 11 and 12 between which extends an elastic 80 13 broken away in Fig. 3 to show the plan view of the support. In both cases in Fig. 95 2 and Fig. 3 the filler member is sewed within a leather member or cloth casing and by provision of the extensions 8 or 9, which extend upward on each side of the foot as will be understood from Fig. 4, the tendency of 100 the pad to move out of place beneath the foot is avoided. Both forms of the device are worn in the same way and are for corrections of the same general type of deformity. Also in both cases the elastic member is 105 preferably used as this enables the pad to be placed on the foot, the elastic webbing strengthening and supporting the foot to a greater or less extent and also stretches as may be required due to the form of the foot 110 or the position of the support thereon. The elastic lies across the top of the foot as will

be readily understood from the foregoing. The lower surface of the support is preferably flat while the pads 6 and 7 in the one case or 6^a as shown in Fig. 3 extend upwardly therefrom as will be understood from Fig. 4.

Having thus briefly described my invention, what I claim and desire to secure by Letters Patent of the United States is—

10 1. A foot support consisting of a member adapted to extend longitudinally of the bottom of the foot and having integral side flaps intermediate its length, a second member of similar outline positioned thereover and the two members stitched together at the edges, an elastic band having its opposite ends secured between the members at the ends of the flaps respectively, a pad of the same general outline as said members held 20 in position therebetween by the stitching and having a thickened portion forward of the flaps lying beneath the metatarsal arch of the foot and an integral thickened portion extending to the rear and providing a support for the longitudinal arch.

2. A foot support consisting of a member having a base portion to be positioned on the under side of the foot longitudinally thereof and integral side flaps, a second member of similar form positioned thereover, the two members being secured together by stitching at the outlying edges thereof, an elastic band, the opposite ends of which are secured between the two members at the flap ends respectively, and a

pad between the said members in the body portion thereof, having a thickened portion for supporting the metatarsal arch, said thickened portion having an outline at its forward end corresponding to that of the 40 forward end of the said two members and lying with its edge adjacent the said stitching and supported thereby from movement, the said pad also having a thinner integral portion thereof extending a slight distance 45 into the base of one of the flaps.

3. A foot support consisting of a flexible member adapted to be positioned to extend longitudinally of the bottom of the foot and having integral side flaps intermediate its length, a second flexible member of similar outline positioned thereover and the two members being stitched together at the peripheral edge, means attached to the two flaps adapted to secure the support 50 on the foot, a pad having the same general outline as said members, the periphery of which extends practically to the said stitching whereby it is held from displacement between said flexible members, said pad consisting of a thickened forward portion for supporting the metatarsal arch of the foot and a thickened rearward portion shaped to support the longitudinal arch of the foot and extending into the base of a flap, said pad 55 also having an integral part extending into the face of the opposite flap.

In testimony whereof, I sign this specification.

LESLIE D. NOBLE.
